LADY'S DRESS

Murray White, Brookline, Mass., assignor to Murray White Co., Inc., Boston, Mass., a corporation of Massachusetts

Application August 20, 1948, Serial No. 148,211

Term of patent 3½ years

(Cl. D3—26)

To all whom it may concern:

Be it known that I, Murray White, a citizen of the United States, residing in Brookline, in the county of Norfolk and State of Massachusetts, have invented a new, original, and ornamental Design for a Lady's Dress, of which the following is a specification, reference being had to the accompanying drawing, forming a part thereof, in which Figure 1 is a front view and Figure 2 is the rear view of a lady's dress showing my new design.

I claim:

The ornamental design for a lady's dress, as shown.

MURRAY WHITE.
